RECEPTACLE

Hilding Larson, Moline, Ill., assignor to Lincoln Locker Corporation, Pocahontas, Iowa, a corporation of Iowa

Application July 2, 1937, Serial No. 151,575

2 Claims.

(Cl. 45—7)

This invention relates to improvements in receptacles and more particularly to improvements in receptacles of the type capable of being shipped in knockdown or disassembled condition.

One of the particular objects of the invention is to provide an improved receptacle construction of the knock down type in which the unit may be assembled by unskilled labor and without tools or other equipment, the various parts automatically locking each other in final position, such parts being readily formed from sheet stock by cutting and bending.

A more particular object of the invention is to provide a type of interlocking fold or grooved channel for the individual elements of a knock down receptacle by which all of the elements may be interlocked and held secure, such receptacle being of especial ruggedness and rigidity.

A further object of the invention is to provide a knock down drawer construction that is entirely assembled by interlocking grooves and in which the front is adapted to be used for the opening and closing of the drawer and with the bottom supported by the sides so that the forces set up by the repeated in and out movement of the drawer are resisted directly by interlocking grooves.

Further objects and advantages of my invention will be apparent from the following disclosure of a preferred form of embodiment thereof, taken in connection with the attached drawings illustrative thereof, and in which,

Fig. 1 is a perspective view of the receptacle in assembled position.

Fig. 2 is a perspective view of the inside of the front of the receptacle partially assembled.

Fig. 3 is a perspective view of the outside of the rear of the receptacle illustrating another step of the assembly.

Fig. 4 is a transverse vertical section through the receptacle looking toward the rear thereof.

Fig. 5 is a longitudinal vertical section through the receptacle before the front is interlocked.

Fig. 6 is a longitudinal vertical section through the receptacle as fully assembled.

Fig. 7 is a vertical cross sectional detail of the rear end of the bottom member and

Fig. 8 is a horizontal cross section on the line 8—8 of Fig. 6 showing the attachment of the front and back elements to the side.

One of the chief advantages of knock down receptacle construction, that it can be shipped in the minimum volume, is often the greatest disadvantage in that assembling requires either

skilled labor and attaching devices, or the completed construction is unstable and of such frail construction that it is readily put out of commission, and will not withstand hard service conditions.

In accordance with one preferred form of embodiment of my invention, I have shown a drawer structure as generally shown in Fig. 1, the elements of which include the side walls 10 and 10a, the front wall 12, the rear wall 14, and the bottom 16. No cover is shown on this construction although it will be apparent that a cover may be provided, if desired.

As shown in Figs. 2 and 4, the bottom 16 is of generally rectangular shape and has a fold 18 of metal which is generally termed a "Philadelphia" fold extending above the plane of the bottom and along each longitudinal edge. Each of these folds includes the upturned marginal portion 18a, and the downwardly and inwardly open portion 18b. These form a channel along the side edges of the bottom with which the sides 10 interconnect. In addition the bottom has an inwardly open fold 20 at its front edge, with the portion 20a extending rearwardly slightly above the plane of the bottom, such fold being adapted to engage the front wall 12 as hereinafter described.

The sides 10 each have a fold 21 along the bottom edge which consists of an outwardly open portion 21a, the height of which is substantially equivalent to the height of the inwardly open fold portion 18b on the bottom. The sides also have outwardly open folds 22 along the front and back vertical edges, which as shown in Fig. 3, cooperate with similar folds 24 and 25 on the adjacent edges of the front and back walls 12 and 14 respectively.

The front wall 12 which may serve as the face of a drawer preferably has a somewhat larger area than does the transverse cross section of the receptacle, the marginal portion being reinforced by folding in the metal with the folds 24 outwardly projecting from the surface along a line inwardly spaced from the edges. The folds 24 each open inwardly and as hereinbefore mentioned, cooperate with the folds 22 on the respective side walls so that a tight interconnection is had between the front wall and side walls. Furthermore, the front wall has a downwardly opening fold 26 at the bottom edge which engages the fold 20 on the bottom 16 when the receptacle is assembled. The edge 29 of metal is bent back on itself at the top of the front for reinforcing reasons. It will also be noted that the other folds are inturned portions of the main body of

the front so that it has smooth edges and is of double thickness around the periphery.

The back 14 of the receptacle is relatively simple in construction, having the two side folds 5 25 which open inwardly and a relatively flat interlocking portion 27 which engages within a channel 28 carried by the bottom as shown in Figs. 3 and 7.

The assembly of the receptacle is as follows: 10 The sides 10 and 10a are first engaged with the bottom 16 but with the bottom extending beyond the forward edge of the sides a substantial amount. The front can then be applied and interlocked with the sides and brought down to 15 the position shown in Fig. 5. By sliding the bottom rearwardly, the folds 20 and 26 are then engaged for a complete connection of the front wall to the bottom and side walls.

After this operation, the back is slid onto the 20 sides, and the interlocking portion 27 engaged within the channel 28 as shown in Fig. 6 which is most simply formed by a welded interior wall. The receptacle is then completed and held in an 25 interlocked manner, no assembly tools or material being required.

It will be noted that the bottom is supported on three sides, including the front so that very substantial weights can be carried thereby. It will also be noted that the front is secured to 30 the receptacle along three sides so that there can be no possibility of an accidental disconnection between the front and the rest of the receptacle. This effectively prevents damage due to the heavy pulling on the drawer front. Furthermore, the receptacle can not be disassembled except by removing the unit from its cabinet as 35 the back must first be raised to release the bottom.

The receptacle is readily made out of sheet 40 metal and can be shipped as knock down material at a very low transportation cost. The elements may be made in large quantities at low cost substantially entirely by a simple cutting and folding operation and the edges or corners are 45 all reenforced. The folds may be changed if desired without changing the nature of the joints, but it is desirable to have the maximum width at the bottom so that the unit may be freely moved in a cabinet as a drawer, and with such an arrangement, folds on the back come into alignment 50 with the folds on the bottom for equal clearance. Furthermore, the inside of the receptacle is entirely smooth, except for the relatively small projection of the fold 26.

55 While I have shown a preferred form of em-

bodiment of my invention, I am aware that modifications may be made thereto and I therefore desire a broad interpretation of my invention within the scope and spirit of the disclosure herein and of the claims appended hereinafter. 5

I claim:

1. A knock down drawer of the class described comprising a bottom member having a transverse inwardly opening fold along the front edge thereof, the side edges of said bottom member being 10 up-turned and folded back on themselves to form longitudinally extending, vertical, inwardly opened channels, a pair of side wall members having outwardly opening folded metal channels along the bottom edges to interengage the channel members on the bottom member, said side wall members also having outwardly opening folded metal channels along the vertical edges, a front wall member having inwardly projecting, 15 inwardly opening, vertical folded metal channels 20 to engage the front, vertical channels on the side wall members, said front wall also having an inwardly projecting, transversely extending, bottom opening channel adapted to cooperate with the transverse fold on the bottom member, and 25 a rear wall member inter-engaging the rear vertically extending channels on the side wall members and the bottom member to prevent disengagement of the front wall member with respect to the bottom member, and thereby prevent the 30 front wall member from disengaging the side wall members.

2. A knock down drawer of the class described comprising side wall members, a bottom wall member, a front wall member, and a rear 35 wall member, the adjacent edges of the respective members having inter-engaging folds whereby the respective members may be assembled by longitudinal movement, the transverse fold along the lower edge of the front wall member and the 40 transverse front edge of the bottom wall member being laterally displaceable rearwardly and the joint between the lower edge of the rear wall member and the rear transverse edge of the bottom wall member being vertically displaceable 45 and normally preventing rearward displacement of the front wall member with respect to the front transverse edge of the bottom wall member, the remaining joints being laterally fixed whereby the rear wall in its connection to the side and 50 bottom walls prevents disengagement of the front wall member and bottom wall member, and thereby locks all the parts together.

HILDING LARSON. 55
